UNITED STATES PATENT OFFICE.

ALONZO HICKS, OF WEST NEW BRIGHTON, NEW YORK, ASSIGNOR TO
E. WILLIS COREY, OF BOSTON, MASSACHUSETTS.

GAME APPARATUS.

SPECIFICATION forming part of Letters Patent No. 290,328, dated December 18, 1883.

Application filed October 4, 1883. (No model.)

To all whom it may concern:

Be it known that I, ALONZO HICKS, of West New Brighton, in the county of Richmond and State of New York, have invented an Improvement in Game Apparatus, of which the following is a specification.

The object of this invention is to provide a game apparatus that will afford amusement and that can be made very inexpensive.

10 I make use of a plate or body of wood or other material, with circular openings through the same and a handle at one end, and at the other end a flexible cord is fastened, to which is attached a ball of rubber or other material.

15 This apparatus is operated by a person grasping the handle, and by a swinging movement causing the ball to ascend above the apparatus, and as the ball descends the endeavor is to catch the ball in one of the openings.

20 In the drawings, Figure 1 is a section through the center of the apparatus, and Fig. 2 is a plan of such apparatus.

The body *a* is of wood or other suitable material, the top and bottom surfaces of which are flat, or nearly so. *b* are the circular openings through the same. *c* is a handle attached to one end of the body *a*. *d* is a flexible or elastic cord fastened near one end of the body *a*, and *e* is a ball attached to the end of such flexible cord.

25 I prefer to make the body *a* and the handle *b* of one piece of material; but the handle may be made of a separate piece and attached to the body in any suitable manner.

30 On the surface of the body *a*, near each opening, is marked a number. I have shown eleven such openings, two numbered 5, four numbered 10, four numbered 20, and one numbered 30; but any number of openings may 35 be employed and numbered as desired.

In operating this apparatus the object is for the person to endeavor to catch and retain the ball in the opening having the highest number. I prefer to use a rubber ball, as the same, unless caught directly in one of the 45 openings, will bound off in striking the apparatus, thus increasing the amusement; but a wooden ball may be employed; or it may be made of any other suitable material. The diameter of the ball *e* is slightly larger than the 50 openings *b*, so that the ball cannot pass entirely through such openings, but only sufficiently far to be retained therein when properly caught by the person using the apparatus.

I do not claim a cup or receptacle for a ball 55 to which a cord is attached; neither do I claim a ring with a handle for catching such ball.

I claim as my invention—

1. The hereinbefore-described game apparatus, consisting of the body *a*, the top and bottom surfaces of which are flat, or nearly so, with numerous circular openings, *b*, through the same, such openings being numbered, the handle *c* at one end, and a flexible cord, *d*, to which is attached the ball *e*, for the purposes 65 set forth.

2. The combination, in a game apparatus, of a body of wood or similar material, having flat or nearly flat top and bottom surfaces, and numerous circular openings through the 70 same, a handle, a flexible cord, and a ball, substantially as specified.

Signed by me this 2d day of October, A. D. 1883.

ALONZO HICKS.
